ERNEST A. HALL, OF TOLEDO, OHIO, ASSIGNOR TO THE COLUMBIA BURNER COMPANY,
OF TOLEDO, OHIO, A CORPORATION OF OHIO

ADJUSTABLE GAS BURNER

Application filed February 16, 1931. Serial No. 516,010.

This invention relates to an adjustable gas burner which is primarily adapted to be used in a furnace or heating plant.

The general object of the invention is to provide a burner which may be expanded or contracted in such a manner as to fit fire pots of various sizes. The present embodiment of the invention, which is adapted to be used in an oblong fire pot, includes oppositely disposed manifolds in spaced parallel relation and so mounted that they may be adjusted toward or from each other in accordance with the width of the particular fire pot in which the burner is to be used.

The specific construction of the invention in its present form, together with the advantages resulting therefrom, will be more particularly described with reference to the accompanying drawing, in which;

Fig. 1 is a plan view of the invention with portions broken away, the furnace structure being shown in section; Fig. 2 is a transverse section taken on the line 2-2 of Fig. 1; Fig. 3 is a vertical section taken longitudinally of the gas supply conduit to one of the manifolds; Fig. 4 is an enlarged sectional view of one of the joints in the conduit.

The invention in its present form is adapted to be used in an oblong fire pot 5 and comprises a plurality of manifolds 6, each having a plurality of spuds 7 inclined upwardly toward the wall of the fire pot. Baffles 8 are arranged above the spuds and as a convenient means for supporting these baffles, each baffle may be provided with a depending flange 9 which is adapted to be inserted between flanges or lugs 10 and 11 formed on the manifold 6.

Gas is supplied through a pipe 12 which leads to a head 13 adapted to be supported from the bottom of the fire pot centrally thereof. In order that the manifolds 6 may be connected to the head 13 and at the same time may be adjustable laterally to accommodate them to the width of the fire pot, it is preferred to form the head 13 with outlet arms 14 having upturned ends 15 from which the respective manifolds 6 are supported by a series of toggles. In the present instance, each toggle comprises a pair of links 16 which

are exactly alike and which constitute a part of the conduit through which the gas is supplied to the manifold. One end of the toggle is connected to the upturned end 15 of the outlet arm 14 and the other end of the toggle 55 is connected to the downturned inlet mouth 17 of the manifold. The links 16 have coengaging ends 18 and 19, one of which seats inside of the other, the larger end of one link seating on the outlet 15 and the smaller end of the 60 other link seating within the manifold inlet mouth 17, whereby to provide a toggle having joints with vertical axes so that each manifold may be adjusted laterally to or from the side wall of the fire pot or longitudinally 65 thereof. It is understood, of course, that suitable gaskets 20 may be provided for the several joints.

For assembling the toggles and for securing them in their adjusted positions, each 70 joint is provided with an axially disposed spindle 21, one end of which is threaded into a thickened portion 22 formed within one of the connecting members, the other end of the spindle projecting through a thickened portion 23 on the other connecting member which is formed with a ground seat for receiving a nut 24, so that the nut may be tightened to secure the connecting members in any adjusted position and also to insure a tight joint 80 that will not leak gas.

The space between the manifolds is covered by a plate 25 the edges of which may rest upon the baffles 8 and which is intermediate supported by lugs 26 formed on 85 the toggle links.

From the foregoing description, it will be seen that I have provided a construction by which the burner may be readily adjusted to accommodate it to any size of fire pot. While 90 in the construction shown, the gas to the manifolds is supplied through the toggles which support the latter, the invention is not necessarily limited to such a construction. The construction of the means by which the manifolds are supported may also be modified without departing materially from the scope of the invention as claimed.

What I claim is:

1. A gas burner comprising a pair of op-

positely disposed manifolds and toggles supporting the respective manifolds, said toggles being individually adjustable in a horizontal plane to vary the position of said manifolds relative to each other.

2. A gas burner comprising a pair of oppositely disposed manifolds, a central gas supply head, and conduits leading from said head to the respective manifolds, each conduit being in a plurality of sections constituting a toggle which is adjustable to vary the distance between the manifold and said supply head.

3. A gas burner comprising a gas supply head, a manifold, and a toggle connecting the manifold to said head, said toggle being formed with a gas passageway therethrough.

4. A gas burner comprising a gas supply head, a manifold, and conduit sections constituting the links of a toggle connecting said head to the manifold.

5. A gas burner comprising a gas supply head, a manifold, and a conduit made in a plurality of sections pivotally connected in series with said head and manifold respectively to constitute a toggle for adjusting the distance between said head and manifold.

6. A gas burner comprising a gas supply head, a manifold, a conduit connecting said head to the manifold, said conduit being jointed to constitute a toggle, each joint including two laterally turned ends, one seating against the other, a spindle constituting the axis of the joint, and means associated

with the spindle for locking the joint and at the same time sealing it against leakage of gas.

7. A gas burner adapted for use in a fire pot and comprising a pair of oppositely disposed manifolds, a common supply head between the manifolds, an intermediate conduit section between each manifold and the supply head, and a pivotal sealed connection between each intermediate conduit section and the head and manifold between which it is located, said manifolds being adjustable about the respective connections to vary the distance between said manifolds and adapt them to fire pots of different widths.

8. A gas burner adapted for use in a fire pot and comprising a gas supply head, a pair of oppositely disposed manifolds, connections including an intermediate conduit section between each manifold and the supply head, and joints between each conduit section and the head and manifold respectively, each joint including two laterally turned ends, one seating against the other, a spindle associated with the spindle for locking the joint and at the same time sealing it against leakage of gas, said manifolds being adjustable about the respective connections to vary the distance between said manifolds and adapt them to fire pots of different widths.

In testimony whereof I have hereunto signed my name to this specification.

ERNEST A. HALL.
